DESIGN FOR A TEXTILE FABRIC

Conrad J. Busch, Wyomissing, Pa., assignor to The Narrow Fabric Company, West Reading, Pa., a corporation of Pennsylvania

Application December 31, 1945, Serial No. 125,223

Term of patent 14 years

(Cl. D47—2)

To all whom it may concern:

Be it known that I, Conrad J. Busch, a citizen of the United States of America, residing at Wyomissing, in the county of Berks and State of Pennsylvania, have invented a new, original and ornamental Design for Textile Fabric, of which the following is a specification, reference being had to the accompanying drawing, forming part thereof.

Figure 1 is a plan view of one side of a portion of a textile fabric showing my new design;

Fig. 2 is a similar view of the other side of said portion of textile fabric.

I claim:

The ornamental design for a textile fabric, as shown.

CONRAD J. BUSCH.
